UNITED STATES PATENT OFFICE

JOHN R. MATHEWS, OF DOVER, NEW HAMPSHIRE, ASSIGNOR TO THE EXPELLO CORPORATION, OF DOVER, NEW HAMPSHIRE, A CORPORATION OF NEW HAMPSHIRE

APPARATUS FOR INSECTICIDE DUSTING RUGS, UPHOLSTERY, AND CLOTHING

Application filed September 27, 1930. Serial No. 484,909.

The present invention relates to insecticide dusting attachments for domestic suction cleaners and the like and the method of using same, and aims generally to provide a device which may be quickly and readily attached to the domestic suction cleaner so that a fine insecticide powder may be blown from the cleaner for treating fabrics, articles of furniture, clothing and the like against moths, insects, vermin, etc.

One of the principal aims and objects of my invention is to provide an attachment or accessory adaptable to the domestic type of suction cleaner for supplying the insecticide or deodorizing powder to the suction inlet and fan chamber of the cleaner in a continuous stream from which it may be forcibly discharged in an air stream through a convenient nozzle attached to the blower side of the cleaner.

As illustrative of one preferred embodiment of the invention reference may be had to the accompanying drawings wherein

Fig. 1 is a side elevation of a suction cleaner with my attachment applied thereto;

Fig. 2 is a vertical sectional view taken centrally through the attachment and a portion of the suction cleaner;

Fig. 3 is a transverse sectional view taken on the line 3—3 of Fig. 1;

Fig. 4 is a horizontal sectional view taken on the line 4—4 of Fig. 1; and

Fig. 5 is a perspective view of the attachment, the powder containing receptacle being shown in position in dotted lines.

In the embodiment of the invention which has been selected for illustrative purposes the attachment preferably comprises a hollow shoe or casing 10 having suitable clamping means 11 for detachably clamping the attachment to the nozzle 12 of a suction cleaner having a fan casing 13 housing a rotatable fan 14 suitably driven by an electric motor 15 as is usual in such devices. The outlet 16 of the fan chamber which usually discharges into the dust bag (not shown) may be fitted with a blower nozzle 17 as is well understood.

The shoe or casing 10 is preferably T shaped having a nozzle sealing portion 18 provided with a suitable gasket 19 of rubber

or like material for effecting an air tight seal against the bottom edge of the suction cleaner nozzle 12 when the attachment is clamped thereto. Suitable positioning lugs 20 are formed on the nozzle sealing portion 18 of the attachment adapted to enter the ends of the suction opening of the nozzle 12 to position the attachment with reference thereto.

The forward part of the attachment is preferably pan shaped terminating in a slotted outlet 21 in the nozzle sealing portion of the attachment and adapted to register with the opening in the nozzle 12 of the suction cleaner. The forward portion of the attachment is provided with an upper closure member 22 having an upstanding receptacle receiving member 23 which may be crimped or screw threaded or otherwise suitably shaped to form a cooperating air tight seal with the open end of a powder containing can or receptacle 24 which is preferably supported on the forward end of the attachment in inverted position. The receptacle 24 preferably is the original container in which the powder is originally packed and may advantageously be in the form of the conventional metal can, glass container, or other package.

The pan shaped end of the attachment is preferably of less width than the slot 21 communicating with the suction nozzle so as to provide within the attachment a forwardly converging suction chamber (see Fig. 4) having an area 25 of concentrated suction immediately adjacent the restricted air inlet 26 in the forward end of the attachment. This area 25 of concentrated suction is axially located with reference to the powder containing receptacle 24.

The receptacle receiving member 23 is provided with a central restricted insecticide supplying orifice 27 through which the powder or other insecticide contained in the receptacle 24 may be drawn into the pan shaped end of the base 10 by action of the centrally arranged area 25 of concentrated suction.

In order to prevent creation of a vacuum in the upper end of the receptacle 24 when powder is used as an insecticide as well as the arching of the powder immediately above the orifice 27, which results in interruption of

the flow of insecticide into the suction chamber 25, I provide an air inlet 28 which preferably takes the form of a goose neck vent 29 having one end secured in the pan shaped portion of the casing 10 and communicating with an opening outside thereof and the other end terminating slightly above the orifice 27 and positioned within the receptacle 24 when the receptacle is in place on the attachment. This vent pipe 29 provides a source of atmospheric air pressure within the receptacle to maintain a pressure differential between the interior of the receptacle and the suction chamber 25 so that the suction within the chamber is effective to create an air stream through the vent pipe 29 and through the orifice 27 during the operation of the fan 14 and prevent congestion of the orifice 27 by the material and maintaining a continuous uninterrupted flow of material through the aperture.

In operation the attachment is readily applied to the suction nozzle 12 of a domestic suction cleaner and securely clamped thereon by clamping means 11, and a can or other container of insecticide is securely attached to the receptacle receiving member 23 in inverted position so that the contents of the receptacle may feed down upon the top of the receiving member 23. At this time with the blower nozzle 17 in place in the outlet 16, the motor 15 and fan 14 may be started, creating a strong suction through the restricted air inlet 26 into the area 25 wherein the suction is most concentrated. As this area 25 is immediately below the orifice 27 in the receptacle receiving member, its effect is to draw the powdered insecticide into the suction chamber 25 where it is entrained in the air current produced by the rotating fan 14 and is drawn into the fan casing 13 and discharged out of the blower nozzle 17. Due to the high speed of rotation of modern domestic suction cleaners the powder is discharged with such velocity that it has the ability to penetrate deeply into the nap of heavy pile fabrics so that moth worms and other insects may be effectively exterminated.

The effect of the suction within the suction chamber 25 of the attachment is to continuously draw air from the receptacle 24 through the orifice 27 and thus create a continuous air current through the vent pipe 29 whose outlet is closely adjacent the orifice 27, preventing the formation of a vacuum within the receptacle 24 and ensuring a continuous flow of powder through the orifice 27.

Advantages of my invention reside in the simplicity of construction and ease with which it may be readily attached to and detached from domestic suction cleaners. The forwardly diverging suction chamber of the attachment which communicates with the slot 21 thereof and which has its area of concentrated suction immediately below the out-

let from the receptacle provides for a generous amount of powder into the suction stream and into the fan casing 13 from which it is discharged through the nozzle 17. By maintaining a source of atmospheric air pressure within the receptacle immediately above the discharge orifice 27, automatic means is provided for maintaining a continuous flow of powder through the orifice without requiring the manipulation of manual devices commonly employed for preventing choking of the material at the discharge orifice.

An insecticide having a base of paradi-chlorobenzene is preferably used as being highly effective in the extermination of moth worms and other insects, as well as being an efficient deodorant. This material is in the form of small crystals, somewhat deliquescent, which have a tendency to stick and congeal in lumps within the receptacle. When the attachment is applied to a suction cleaner, the suction created through the neck 29 is effective to maintain a continuous air stream through the orifice 27, preventing the sticking together of the crystals and maintaining a continuous uninterrupted flow of crystals through the orifice 27 into the casing 10. Obviously the larger lumps or crystals drawn into the fan casing 13 are broken down by the fan 14 into a finer powder, so that the insecticide may penetrate effectively into the nap of a deep pile fabric.

Although I have described my invention with reference to a preferred embodiment thereof it is apparent that other equivalent arrangements embodying the novel features are to be included as well.

I claim:

1. In combination with a differential pressure device, a powder dusting attachment therefor comprising a hollow casing detachably connected with the intake of said device, said casing being of varying cross-sectional area to provide a region of concentrated suction, and means for supplying powder to said casing at the region of concentrated suction.

2. In combination with a differential pressure device, a powder dusting attachment therefor whereby insecticide powder may be blown through said device, comprising a hollow casing removably connected at one end with an intake passage of said device, an air inlet at the remote end of said casing, a receptacle supporting member connected with said casing and having suction communication with said casing, and a powder receptacle detachably connected with the supporting member.

3. A powder dusting attachment for differential pressure devices comprising a hollow casing removably connected to an intake passage thereof, a support for a powder receptacle having a passage communicating with said casing, an air inlet to said casing, and an

- air inlet in said support for admitting air to said powder receptacle when the latter is in operative position on said support.
4. A powder dusting attachment for differential pressure devices comprising a hollow casing removably connected to an intake passage thereof, a support for a powder receptacle having a passage communicating with said casing, an air inlet to said casing, and an air inlet tube in said support for admitting air to said powder receptacle when the latter is in operative position on said support, said air inlet tube terminating in proximity to said passage.
5. A powder dusting attachment for differential pressure devices comprising a hollow casing removably connected to an intake passage thereof, a support for a powder receptacle having a passage communicating with said casing, an air inlet to said casing, said air inlet having a contracted mouth, and an air inlet in said support for admitting air to said powder receptacle when the latter is in operative position on said support.
6. Apparatus for dusting or dry spraying insecticide powders comprising a differential pressure device, and means detachably connected with said device providing a suction chamber, an orifice communicating therewith, and auxiliary air suction means for supplying insecticide powder through said orifice in a continuous uninterrupted stream.
7. A powder diffusing attachment for differential pressure devices comprising a casing having an air inlet and an outlet connected to the inlet passage of the device, a mixing passage in said casing between said air inlet and outlet, a support for a powder receptacle, an orifice in said support discharging into said mixing passage, and an air supply extending through said support and discharging in proximity to said orifice.
8. A powder diffusing attachment for differential pressure devices comprising a casing having an air inlet and an outlet connected to the inlet passage of the device, a mixing passage in said casing between said air inlet and outlet, a support for a powder receptacle having an open top and means associated therewith for retaining the powder receptacle on said support in inverted position to close its open top, an orifice in said support discharging into said mixing passage, and an air supply extending through said support and discharging in proximity to said orifice.
9. A powder diffusing attachment for differential pressure devices comprising a casing having an air inlet and an outlet connected to the inlet passage of the device, a mixing passage in said casing between said air inlet and outlet, the top wall of said passage constituting a support for a powder receptacle, an orifice in said top wall, and an air supply extending through said support and discharging in proximity to said orifice.
10. A powder diffusing attachment for a differential pressure device comprising a casing having an air inlet and an outlet connected to the inlet passage of the device, a mixing passage in said casing between said air inlet and outlet, a support for a removable powder receptacle, an orifice in said support discharging into said mixing passage, and means for retaining the powder receptacle on said support.
11. A powder diffusing attachment comprising a casing having an air inlet and an outlet, a mixing passage in said casing between said air inlet and outlet, a support for a removable powder receptacle, an orifice in said support discharging into said mixing passage, and means for retaining the powder receptacle on said support.
12. A portable powder projector comprising a differential pressure device, a discharge nozzle connected to the outlet from said device, a mixing passage connected to the intake of said device, an orifice in the top wall of said mixing passage, an air pipe discharging downwards immediately above said orifice, and means for positioning a powder receptacle to maintain a supply of powder around said pipe and orifice.
13. A portable powder projector comprising a differential pressure device, a discharge nozzle connected to the outlet from said device, a mixing passage connected to the intake of said device, an orifice in the top wall of said mixing passage, an air pipe discharging downwards immediately above said orifice, and means for positioning a powder receptacle to maintain a supply of powder around said pipe and orifice, said positioning means including a protuberance constituting a closure for said receptacle having slightly tapered side walls which enter and frictionally engage in an opening in said receptacle.
14. In an insecticide duster in combination with an adapter for attachment to a suction intake opening in the housing of a differential pressure device, said adapter comprising a casing having an outlet leading to said suction intake opening, an inlet for admitting air to said casing, an orifice for admitting insecticide powder and the like to said casing, means surrounding said orifice constituting a support for a loose material supply, and air suction means for maintaining a constant supply of material through said orifice.
- In testimony whereof, I have signed my name to this specification.
- JOHN R. MATHES.
